(57) **CLAIM**

The ornamental design for a backpack, as shown and described.

DESCRIPTION

FIG. 1 is a front perspective view of a backpack according to a first embodiment of the present invention;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a front perspective view of a backpack according to a second embodiment of the present invention;

FIG. 8 is a front elevation view of the embodiment of FIG. 7;

FIG. 9 is a rear elevation view of the embodiment of FIG. 7;

FIG. 10 is a right elevation view of the embodiment of FIG. 7; and,

FIG. 11 is a left elevation view of the embodiment of FIG. 7.

The broken lines in the drawings depict portions of the backpack that form no part of the claimed design.
